UNITED STATES PATENT OFFICE.

OTTO R. GRASS, OF EVANSTON, ILLINOIS, ASSIGNOR OF ONE-HALF TO LEIGH HUNT, OF CHICAGO, ILLINOIS.

AUTOMATIC PHONOGRAPH STOP.

Application filed February 3, 1922. Serial No. 533,842.

To all whom it may concern:

Be it known that I, OTTO R. GRASS, a citizen of the United States, residing at Evanston, in the county of Cook and State of Illinois, have invented a certain new and useful Improvement in Automatic Phonograph Stops, of which the following is a specification.

My invention relates to automatic stops for phonographs, and particularly to a stop which is adjustable and which includes a combined indicator and control whereby the stop may be set to stop the rotation of the record at any predetermined point. Other objects will appear from time to time in the course of the specification.

I illustrate my invention more or less diagrammatically in the accompanying drawings, wherein—

20 Figure 1 is a plan view of my device;

Figure 2 is a similar plan view with the stop set at a different position;

Figure 3 is a section on the lines 3—3 of Fig. 2;

25 Figure 4 is a section on the lines 4—4 of Fig. 2.

Like parts are indicated by like characters throughout the drawings and specification.

30 A is a tone arm of a phonograph, rotatable on the axis A¹. B is a plate secured by any suitable means to the top of the phonograph casing. C is the periphery of the turntable.

35 Pivoted on the plate B, at D, is a block D¹, which is apertured as at D² D³, said apertures extending horizontally along either side of the pivot pin D. Penetrating them are the parallel pins E E¹, which are secured to a cross-arm or block E², on which is pivoted a stop arm E³ having a quadrant portion E⁴ slotted as at E⁵. Penetrating the member E² and passing through the slot E⁵ is a screw or other locking means E⁶, whereby the quadrant may be adjustably locked in place. Upwardly projecting from the stop arm E³ is the stop E⁷, adapted to be engaged by the tone arm, as shown in Fig. 2.

40 Pivoted to the cross-bar E² is a longitudinal bar F, the outer end of which is toothed to form a rack F¹ in mesh with a pinion F², to which is adjustably secured an indicator arm F³ adapted to be rotated by the pinion about a graduated indicating

disk F⁴, the pinion and arm being secured against rotation on a shaft F⁵ which penetrates the indicating disk or dial. A thumb screw F⁶ permits the indicating arm to be adjusted in relation to the pinion and rack. 60

Rigidly secured to the opposite side of the pivot plate D is the arm G, which is notched to engage a stop G¹, in contact with which it is normally held by any yielding means, such as the spring G². It 65 terminates in an arcuate portion G³, the outer end of which is adapted to engage an upwardly projecting lug H on the pivot plate H¹. H¹ is provided with a handle H² in rigid relation thereto, and an arm H³, 70 upwardly projecting from which is the member H⁴ adapted, when in one position, to engage the edge of the turntable and stop it. It may be made of rubber or any other frictional material. Another arm H⁵ projects from the pivoted disk H¹ and has secured to it the spring H⁶, the opposite end of which is fastened to the plate B, 75 as at H⁷.

It will be obvious that while I have illustrated and described an operative device, many changes might be made in the number, size, shape, relation and disposition of parts, without departing from the spirit of my invention. 80

The use and operation of my invention are as follows:

The turntable engaging member H⁴ is normally kept out of contact therewith during the rotation thereof by the engagement 90 of the lug H with the arcuate end of the arm G, which is held against the stop G¹ by the spring G². The latch is tripped by the tone arm, which, as it approaches the center of the turntable on the completion of 95 the playing of the disk, contacts the vertical stop E⁷ and thereby rotates the plate D through the parallel pins and moves the arm G against the spring G², away from the stop G¹ and out of contact with the lug H. The 100 spring H⁶ then rotates the plate H¹ and brings the member H⁴ in contact with the edge of the turntable, to stop its rotation.

The vertical stop E⁷ may be adjusted for 105 various sizes of machine and various diameters and shapes of tone arm, by rotating it on its pivot and setting it in fixed position by means of the screw and quadrant. The stop is accurately set for any size of record by initially setting the indicating arm or 110

needle. Arbitrarily taking 45 as a number, as shown in Fig. 2, the vertical stop E⁷ is set in a position to be tripped by the tone arm at the end of a relatively short record. 5 Where the record is longer, the indicating arm or needle may be rotated about to the position 5, for example as shown in Fig. 1. This rotation, through the pinion and the rack, gives an axial motion to the longitudinal bar F in the direction of the pivot plate D and moves the parallel pins E and E¹ further into the apertures D² and D³ on either side of the pivot. The vertical stop is thereby moved nearer the center of the machine and is not reached by the tone arm until after a longer excursion thereof. When the size of the record has been determined by experiment, the proper index mark may be put thereon and when it is 10 played again the indicating finger may be moved to the appropriate position.

When the tone arm has been withdrawn and a new record is in place, the machine may be started by the use of the handle H², 25 which rotates the plate H¹ until the lug H passes beyond the arcuate end G³, and the spring G² then forces the arm G against the stop G¹. The spring H⁶ then pulls the lug H against the end G³ and it remains in that 30 position until again tripped by the tone arm.

I claim:

1. An adjustable pivot connection comprising a pivoted member, a plurality of apertures therein at either side of the pivot, 35 and a plurality of pins, one adapted to penetrate each of said apertures and to be longitudinally adjustable therealong in unison.

2. An adjustable turn table brake tripping connection for phonographs comprising a pivoted member, a plurality of apertures therein at either side of the pivot, and a plurality of pins adapted one to penetrate each of such apertures and to be longitudinally adjusted therealong in unison.

45 3. An adjustable turn table brake tripping connection for phonographs comprising a pivoted member, a plurality of apertures therein at either side of the pivot, and a plurality of pins adapted one to penetrate each of such apertures and to be longitudinally adjusted therealong in unison, and an indicating member connected to said pins.

4. An adjustable turn table brake tripping connection for phonographs comprising a pivoted member, a plurality of apertures therein at either side of the pivot, and a plurality of pins adapted one to penetrate each of such apertures and to be longitudinally adjusted therealong in unison, an indicating member connected to said pins, an indicating dial and an indicating finger rotating thereabout, and a rack and pinion connection between said finger and said indicating member.

5. An adjustable turn table brake tripping

connection for phonographs comprising a pivoted member, a plurality of apertures therein at either side of the pivot, and a plurality of pins adapted one to penetrate each of such apertures and to be longitudinally adjusted therealong in unison, and an indicating member pivotally connected to said pins.

6. An adjustable turn table brake tripping connection for phonographs comprising a pivoted member, a plurality of apertures therein at either side of the pivot, and a plurality of pins adapted one to penetrate each of such apertures and to be longitudinally adjusted therealong in unison, an indicating member pivotally connected to said pins, an indicating dial and an indicating finger rotating thereabout, and a rack and pinion connection between said finger and said indicating member.

7. An adjustable turn table brake tripping connection for phonographs comprising a pivoted member, a plurality of apertures therein at either side of the pivot, and a plurality of pins adapted one to penetrate each of such apertures and to be longitudinally adjusted therealong in unison, and an indicating member pivotally connected to said pins, a projecting stop associated with said pins.

8. An adjustable turn table brake tripping connection for phonographs comprising a pivoted member, a plurality of apertures therein at either side of the pivot, and a plurality of pins adapted one to penetrate each of such apertures and to be longitudinally adjusted therealong in unison, an indicating member pivotally connected to said pins, an indicating dial and an indicating finger rotating thereabout, and a rack and pinion connection between said finger and said indicating member, a projecting stop associated with said pins.

9. An adjustable brake tripping connection for phonographs comprising a pivoted member, a plurality of apertures one on each side of the pivot, parallel pins adapted to be longitudinally adjusted in unison along said apertures, indicating means pivotally connected to said pins, an indicating dial, a finger, and a rack and pinion connection between said finger and said indicating means, and a trip stop adjustably mounted on said indicating means.

10. An adjustable brake tripping connection for phonographs comprising a pivoted member, a plurality of apertures one on each side of the pivot, parallel pins adapted to be longitudinally adjusted in unison along said apertures, indicating means pivotally connected to said pins, an indicating dial, a finger, and a rack and pinion connection between said finger and said indicating means, and a trip stop adjustably mounted on said indicating means, a trigger element in rigid

connection with said pivoted member, and yielding means adapted to hold it normally in operative position.

11. In a trip for phonographs, a stop element adapted to contact the tone arm of the phonograph, a brake element adapted to engage the turn table of the phonograph and a tripping connection between such stop and such brake, the stop comprising a horizontal portion and a vertical portion adapted to be engaged by said tone arm, the horizontal portion being pivoted at one point to the tripping connection and having an adjusting quadrant and slot for adjusting it to various sizes and positions of tone arm.

12. An adjustable stop mechanism for

phonographs, comprising a pivoted trigger element, a pivoted brake element adapted to be held normally inoperative thereby, a tone arm, a stop on said trigger element adapted to be contacted thereby to release the brake at the expiration of the playing excursion of the tone arm, yielding means adapted to hold the trigger element normally in operative engagement with the brake element and a stop against which said trigger element is adapted to be positioned normally to align it with said brake element.

Signed at Chicago, county of Cook, and State of Illinois, this 25th day of January, 1922.

OTTO R. GRASS.
